(57) **CLAIM**

The ornamental design for an applicator, as shown and described.

DESCRIPTION

FIG. 1 is a perspective view of an applicator showing my new design.

FIG. 2 is a front view of FIG. 1 thereof.

FIG. 3 is a back view of FIG. 1 thereof.

FIG. 4 is a right side view of FIG. 1 thereof.

FIG. 5 is a left side view of FIG. 1 thereof.

FIG. 6 is a top view of FIG. 1 thereof; and,

FIG. 7 is a bottom view of FIG. 1 thereof.

The features shown in broken lines depict environmental subject matter only and form no part of the claimed design.
